UNITED STATES PATENT OFFICE.

PAUL A. BANCEL, OF NEW YORK, N. Y., ASSIGNOR TO THE BABCOCK & WILCOX COMPANY, OF BAYONNE, NEW JERSEY, A CORPORATION OF NEW JERSEY.

CROSSFLOW SUPERHEATER.

Application filed May 23, 1913, Serial No. 769,535. Renewed November 27, 1917. Serial No. 204,977.

To all whom it may concern:

Be it known that I, PAUL A. BANCEL, a citizen of the United States, residing at New York city, county and State of New York, have invented certain new and useful Improvements in Crossflow Superheaters, of which the following is a full, clear, and exact description.

The invention, which constitutes the subject matter of this application, relates to an apparatus which I prefer to call a cross flow superheater. The invention consists broadly of an apparatus for absorbing heat from hot gases by providing a boiler with a plurality of paths in which the boiler tubes are located and through which the furnace gases pass from the furnace to the smokestack, the boiler being so constructed or means being so provided as to create an unbalanced pressure in said paths whereby a portion of the gases passes from a point of higher pressure to a path of lower pressure over a heat absorbing means. In the construction shown the heat absorbing means consists of a superheater but it is to be understood that the invention is not limited to the absorption of the heat for superheating purposes. It will therefore be seen that the theory upon which the invention is predicated consists in the provision of mechanism for the flow of a fluid, the flow through said mechanism comprising a main stream, a plurality of subsidiary streams, and a connection between streams in which a flow is obtained dependent on both the total flow and the separate flows in the subsidiary streams.

In the annexed drawings, which show the preferred embodiment of my invention,

Fig. 1 illustrates a longitudinal vertical sectional view of a known form of horizontal water tube boiler.

Fig. 2 is a section on the line 2—2 of Fig. 1 showing the application of my invention.

Fig. 3 is a section on line 3—3 of Fig. 1, Fig. 4 is a diagrammatic view of the main and subsidiary paths for the flow of gases from the furnace to smokestack.

Fig. 5 is a perspective view of my invention as adapted to a known form of water tube boiler, the walls of the boiler having been omitted in this view to show more clearly the interior construction.

Referring to the construction shown in Figs. 1 and 2 the reference numeral 10 des-

ignates the drum, 11 the front header, 12 the rear header, 13 the boiler tubes connecting the respective headers, 14, 15 and 16 the baffles, and 17 the furnace of an illustrative form of water tube boiler, all of which are inclosed in a suitable structure or setting 18. As shown in Fig. 2 a part of the boiler surface is divided longitudinally and centrally to provide a superheater chamber 19. As a result of this division the central baffle 15 of Fig. 1 is divided into two portions 20 and 21, while the upper baffle 16 of Fig. 1 is preferably divided into two portions, 22 and 23. This arrangement of the baffles in conjunction with the vertical baffles 24 and 25 divides the boiler surface into four distinct chambers A, B, C and D, through which the gases pass to the smokestack 26. The respective chambers are so arranged that a portion of the gases which enter the chamber A flows across the superheater chamber among the superheater elements. Located in the superheater chamber 19 I provide a superheater comprising the usual superheater tubes or elements 27, and usual headers 28, 29. The respective chambers A, B, C and D are so arranged and proportioned that a certain percentage of the gases flowing into chamber A is forced to flow across the superheater chamber 19 into boiler chamber C, and in doing so passes among the superheater elements 27. This arrangement can best be explained by taking a concrete case. Suppose it is estimated that a sufficient superheat could be obtained by passing about 20% of the total volume of the furnace gases over the superheating tubes. Under these conditions the chamber A is designed to receive 60% of the furnace gases while the chamber B receives only 40%. Inasmuch as the chamber C is of the same size as chamber A, and the chamber D is the same size as chamber B, said chambers C and D are adapted to receive 60% and 40% of the gases respectively. Since the chamber B is adapted to receive only 40% of the gases from chamber A, 20% of the gases from the latter will flow across the superheater chamber 19 to the pass C and inasmuch as this latter pass receives only the gases (40%) from pass D it will at once be apparent that the pressure therein is such as to augment the flow of gases across the superheater. In other words, if passes A and C are each de-

signed to receive 60% of the furnace gases and passes B and D are each designed to receive 40% of the gases it will at once be apparent, everything else being equal, that 5 there will be a flow of 20% from pass A to pass C by way of chamber 19.

From the above description it will be seen that the boiler is divided longitudinally into a plurality of paths in which the boiler 10 tubes are located and through which the furnace gases pass from the furnace to the smokestack. The heated gases pass in a single stream from the furnace to and beyond the baffle 14 when the same is divided 15 into subsidiary or branch streams, one of which is represented by the letters A—B and the other by the letters C—D. Between these subsidiary paths and connecting the same is a chamber in which the heat 20 absorbing means, heretofore referred to, is located. In Fig. 4 I have illustrated these paths or streams diagrammatically in which M is the main path A—B and C—D the 25 subsidiary or branch paths, and H the connection between any two of the said main and subsidiary streams. The coils in this figure represent hydraulic resistances, such as 30 tubular heating surfaces. It will therefore be understood that the gases from the furnace pass into the superheater chamber 19 by way of the perforation 32, near one of the vertical baffles 24, which is clearly shown in Figs. 1 and 3. The gases then flow longitudinally of said superheater chamber to 35 the opposite end thereof and escape therefrom through the perforation 33 in the vertical baffle 25, which is clearly illustrated in Figs. 1 and 2.

In order to regulate the superheat, or 40 what amounts to the same thing, to control the cross flow of gases over the superheater, I provide two dampers 30 and 31 in the uptake 26.

I have considered above that 20% of the 45 gases flow across the superheater at some normal load and normal superheat. I shall now consider the operation of my invention as the boiler load is increased. With the regulating dampers 30 and 31 wide open 50 the total draft is increased so that more coal is burned and more gases flow through the boiler and more steam is generated. It will be apparent (therefore) that if the total volume of gases be doubled the volume of 55 gases flowing over the superheater will also be doubled. But, owing to the fact that with greater loads the temperature of the gases goes up in all regions of the boiler they would also go up at the entrance of 60 the superheater and therefore with the volume of the gases doubled and their temperature raised somewhat the temperature of the superheated steam would rise. This is the common undesirable characteristic of 65 combined superheaters.

If 20% of the gases have to flow over the superheater at normal load in order to give a rated superheat, it might be that only 15% of the gases have to flow over the superheater to give the same superheat at double the load. 70 The desired decrease in per cent of gases flowing over the superheater tubes would be obtained by a slight closing of the damper 31 on the left hand side of the boiler. This closing of the damper will decrease the 75 draft on that side of the boiler and hence the proportion of steam made by the decreased draft. Furthermore, the rise of temperature of the gases flowing over the superheater at heavy load will in itself tend 80 to decrease the per cent flow, even with the damper unchanged, because the higher temperature means a larger volume and velocity of the gases, and therefore an increased 85 resistance to flow.

With decrease in boiler load the natural tendency would be for the superheat to fall off. This can be taken care of by a slight closing of the damper 30 of the right hand side of the boiler, thus forcing a greater 90 volume of the gases over the superheater tubes. By closing this damper at any load the superheater can be increased by a larger amount if so desired. On the other hand the flow of gases over the superheater tubes 95 can be stopped entirely by a sufficient closure of the damper 31 on the left hand side of the boiler. It should be noted, however, that even with this condition, the right hand side of the boiler will still be doing considerable work, that is the load will not be entirely thrown on the left hand side for it is obvious 100 that the damper 31 will only have to be closed sufficiently to make the pressure in C the same as the pressure in A so that there will 105 be no difference of pressure across the superheater. Evidently there will still be a considerable flow of gas over the right hand boiler surface, although this flow would be somewhat less than the flow over the left 110 hand side.

In the constructions shown a boiler is illustrated as having two drums. It is to be understood, however, that the invention is not limited to boilers with two drums for it 115 is obvious that it is equally feasible to apply the invention to boilers wherein any number of drums are employed. Furthermore I make no specific claims to the baffles shown herein, nor do I restrict myself to 120 the type shown as the use of one kind of baffle in preference to another is merely the mechanician's or designer's choice of features.

The boiler shown in the drawing is merely illustrative and it will be obvious that my 125 invention may be applied to other forms of boiler and to any apparatus for absorbing heat as might be formed by a combination of boiler, economizer, air heater or superheater.

What I claim is:

1. An apparatus for absorbing heat from hot gases comprising a boiler provided with boiler tubes and with means forming a plurality of paths through which the gases pass from the furnace to the smokestack, in combination with heat absorbing means located between said paths, and regulable means for deflecting a portion of the furnace 10 gases over said heat absorbing means into one of the said paths of the boiler. 70
2. An apparatus for absorbing heat from hot gases comprising a boiler provided with boiler tubes and with means forming a plurality of paths in which the boiler tubes are located and through which the furnace gases pass from the furnace to the smokestack, in combination with heat absorbing means located between said paths over 20 which a portion of the said gases are adapted to pass from a point of higher pressure to a path of lower pressure. 75
3. An apparatus for absorbing heat from hot gases comprising a boiler provided with boiler tubes and with means forming a plurality of paths in which the boiler tubes are located and through which the furnace gases pass from the furnace to the smokestack, in combination with heat absorbing 30 means located between said paths through which a portion of said gases are adapted to pass from a point of high pressure to a path of low pressure, and means for regulating the flow of gases through said heat absorbing means. 80
4. An apparatus for superheating steam comprising a boiler provided with boiler tubes and with a plurality of paths in which the boiler tubes are located and through 40 which the furnace gases pass from the furnace to the smokestack, in combination with a superheater located between said paths, and means for deflecting a portion of the gases from one path over the superheater 45 to the other path. 85
5. An apparatus for superheating steam comprising a boiler provided with boiler tubes and with means forming a plurality of paths in which the boiler tubes are located and through which the furnace gases are adapted to pass from the furnace to the smokestack, in combination with a superheater chamber between said paths and 50 through which a portion of the furnace gases are adapted to pass from a point of higher pressure to one of said paths in said boiler, and a superheater in said superheater chamber. 90
6. An apparatus for superheating steam comprising a boiler provided with boiler tubes and with a plurality of paths in which the boiler tubes are located and through 60 which the furnace gases are adapted to pass from the furnace to the smokestack, a superheater chamber connecting said paths, 65
- said paths so constructed as to maintain an unbalanced pressure between said paths whereby a portion of the gases flow from one path through said superheater chamber into the other path, and a superheater located in said superheater chamber. 70
7. An apparatus for superheating steam comprising a boiler provided with boiler tubes and with a plurality of paths in which the boiler tubes are located and through 75 which the furnace gases are adapted to pass from the furnace to the smokestack, a superheater chamber through which a portion of the gases are adapted to pass from one of said paths to the other, a superheater in said chamber, and means for throttling the flow of gas through one path to regulate the flow of gases through said superheater chamber. 80
8. An apparatus for absorbing heat from hot gases comprising a boiler divided longitudinally to the flow of furnace gases from the furnace to the smokestack, in combination with a superheater chamber located between said divided portions of the boiler and through which a part of the gases is adapted to flow, boiler tubes located in said portions, a superheater located in said superheater chamber, and means for varying the pressures in said portions whereby the flow of gases through said superheater chamber is 90 regulated. 95
9. An apparatus for absorbing heat from hot gases comprising a boiler provided with a main path for the furnace gases, subsidiary paths branching from the same, a connection between two of said paths in which a flow is obtained dependent upon both the total flow and the separate flows in the subsidiary paths, and a heat absorbing means in said connection over which the gases flowing therethrough are adapted to pass. 100
10. An apparatus for absorbing heat from hot gases comprising a boiler provided with a main path for the furnace gases, subsidiary paths in which tubular heating surfaces are located and branching from said main path, a connection between two of said paths in which a flow is obtained dependent upon both the total flow and the separate flows in the subsidiary paths, and a heat absorbing means in said connection over which the gases flowing therethrough are adapted to pass. 110 115
11. An apparatus for absorbing heat from hot gases comprising a boiler provided with a main path for the passage of furnace gases, tubular heating surfaces located in said path, subsidiary paths in which tubular heating surfaces are also located, said subsidiary paths branching from the main path, a connection between two of said paths in which a flow is obtained dependent upon both the total flow and the separate flows in the subsidiary paths, and a heat absorbing means in said connection over which the 120 125 130

- 4
- gases flowing therethrough are adapted to pass.
  - 12. An apparatus for absorbing heat from hot gases comprising a horizontal water tube boiler provided with a plurality of horizontal baffles which divide the said boiler into a main and subsidiary paths for the passage of the furnace gases therethrough, a connection between two of said paths in which a flow is obtained dependent upon both the total flow and the separate flows in the subsidiary paths, and a heat absorbing means in said connection over which the gases flowing therethrough are adapted to pass.
  - 10
  - 15

13. An apparatus for absorbing heat from hot gases comprising a horizontal water tube boiler provided with a plurality of horizontal and vertical baffles which divide said boiler into main and subsidiary paths for the passage of the furnace gases therethrough, said vertical baffles defining a superheater chamber which establishes a connection between two of said paths in which a flow is obtained dependent upon both the total flow and the separate flows in the subsidiary paths, and a superheater in said chamber over which the gases are adapted to flow.
